(57) **CLAIM**

The ornamental design for a massage pillow, as shown and described.

DESCRIPTION

FIG. 1 is a front elevation view of a massage pillow; FIG. 2 is a rear elevation view of FIG. 1;

FIG. 3 is a left side elevation view of FIG. 1;

FIG. 4 is a right side elevation view of FIG. 1;

FIG. 5 is a top plan view of FIG. 1;

FIG. 6 is a bottom plan view of FIG. 1; and,

FIG. 7 is a perspective view of FIG. 1.

In the drawings, the broken lines represent portions of the article which form no part of the claimed design.

1 Claim, 6 Drawing Sheets(56)
